UNITED STATES PATENT OFFICE.

SALVADOR RAGONA, OF NEW YORK, N. Y.

CIGARETTE-MACHINE.

1,134,638.

Specification of Letters Patent.

Patented Apr. 6, 1915.

Application filed October 9, 1908. Serial No. 456,858.

To all whom it may concern:

Be it known that I, SALVADOR RAGONA, a citizen of the United States, residing in the borough of Manhattan, in the city, county, 5 and State of New York, have invented certain new and useful Improvements in Cigarette-Machines, of which the following is a specification, reference being had to the accompanying drawings, which form a part 10 thereof.

My invention relates to cigarette machines and more particularly to a type thereof patented to me in and by Letters-Patent of the United States No. 869,394, of October 29, 15 1907, for placing tips of cork, or other similar material, on cigarettes to form the mouth-piece therefor. In the operation of the machine described in said Letters-Patent, I have found the number of "seconds" is increased 20 by reason of the inability of the unskilled operator to adjust and arrange cigarettes upon the conveyer belt with a rapidity commensurate with the speed of operation of the machine, this limitation resulting, in some instances, in the failure to keep 25 the chute alined with the holder supplied constantly with cigarettes, or the delivery of cigarettes to said chute, at an angle, thus resulting in the mutilation of the cigarette 30 by the pusher-rod. This not only destroyed the cigarette, but clogged the holder and scattered particles of tobacco upon the wrapping mechanism to an extent to require an occasional stoppage of the machine for the 35 purpose of cleaning the holder and the chute and cleaning the mechanism. I have also found that through the irregularities of the packing of the cigarette rope the flexible wiper, in some instances, in case the cigarette 40 is large and hard, breaks the end of the cigarette slightly; or in case the cigarette is small and loosely packed, the end of the tipping material will not be caused to adhere thereto and the withdrawal of the tip-carrier 45 would fail to measure out the proper length of strip, thus failing to cover the entire end of the cigarette. I have also found that, through the absence of a collecting mechanism, additional labor is required to operate 50 the machine, and an unnecessary handling of the cigarette is occasioned. In addition to these difficulties imposed by the limitations of unskilled labor, I have found that owing to the irregularity in the lengths of the cigarette 55 produced on the ordinary cigarette machine, the extent of projection of suc-

sive cigarettes from the holder varies, thus causing the location of the mouth-piece to vary slightly in a small percentage of cigarettes tipped.

The main object of my present invention is to improve the machine set forth in my said Letters-Patent by such a variance in the mechanism and the addition of such elements as will obviate these difficulties, above 60 specified, and thus increase the efficiency of the machine by reducing to a minimum the attention required to operate same, and reducing the number of seconds through breakage or the improper wrapping of the mouth-piece strip about the end of the cigarette. 70

A further object of the invention is to provide a conveyer belt by means of which cigarettes will be automatically fed relative to the holder adjacent to the wrapping mechanism and hold the cigarette, while retained on the said conveyer-belt, in alinement with the said holder, so as to permit each cigarette to be ejected directly from the conveyer-belt to the said holder, thus eliminating the 80 receiving chute and the breakage of cigarettes resulting from the use of such.

A still further object is to provide, in a machine of this character, a conveying-belt of the character above referred to, which 85 will be operated intermittently to afford ample time for the transfer of the cigarette therefrom to the holder, the operation of which belt will be synchronized with that of the remaining mechanism. 90

A still further object is to provide, in a machine of this character, a conveying-belt wherein the cigarettes will be accurately positioned and held in the proper position to be ejected directly from the belt to the cigarette 95 holder, and yet permit said cigarettes to be individually turned so that they may be delivered to the holder, if desired, in a position whereby the seam on each cigarette and of the cork tip will be coincident. 100

A still further object is to provide in a cigarette machine of this character, a collecting mechanism which will receive the completed product of the machine and deliver it to a collecting belt in such a position 105 as to have the cigarette drop directly upon said belt in a manner to avoid that skewing of the cigarette which would result were one end of the cigarette to contact with said belt prior to the other. 110

A still further object is to provide in a collecting mechanism of this character a receiv-

ing device, which will true up each cigarette as it is delivered thereto and automatically deposit it in the desired position upon a collecting belt.

5 A still further object of the invention is to provide a member, the operation of which is synchronized with that of the wiper, which will engage the side of the cigarette opposite to that upon which the wiper is used, and 10 hold the cigarette perfectly rigid while the free end of the strip is being applied thereto; thus preventing the breaking of the cigarette, or such a give thereto as would result in the failure of the wiper to cause the strip 15 end to adhere to the cigarette.

15 A still further object is to provide, in a machine of this character, a member which will simultaneously hold the strip against a backward movement and release the fingers carried by the strip carrier so that under all conditions the length of the severed portion of the strip will be the same.

20 A still further object is to provide a simplified mechanism to prevent the "piling" 25 of cigarettes adjacent to the outlet of the hopper.

25 A still further object of the invention is to provide a machine of this character wherein the cigarettes will be fed from a 30 hopper having a movable bottom and a mechanism adapted to receive cigarettes from said movable bottom, true them up and deposit them upon a conveyer-belt in the proper position to be fed relative to the 35 holder.

35 A still further object is to provide a machine embodying a holder to which the cigarettes are fed one at a time with one end 40 projecting therefrom wherein each cigarette, irrespective of a variance in the length of different cigarettes, will be automatically positioned in said holder with the end projecting therefrom to a uniform predetermined extent.

45 A still further object is to provide, in a machine of this character, a mechanism for adjusting the cigarette to the holder, as above described, the operation of which will be synchronized with that of the remaining 50 mechanism in a manner to cause it to be out of the way of said mechanism during the wrapping operation, and operative at a time when the cigarette is loosely held in the holder.

55 A still further object is to provide a mechanism of this character adapted to accomplish such an adjustment of the cigarette without imparting thereto such momentum as would tend to restore the cigarette to the 60 holder to an extent greater than desired. And a still further object of the invention is to provide, in a machine of the character described in my said Letters-Patent, such additions and improvements as will render the 65 same more nearly automatic and minimize

the loss through breakage, or otherwise, attendant upon the employment of unskilled labor.

70 The invention consists in the novel features of construction and combination of parts hereinafter set forth and described and more particularly pointed out in the claims hereto appended.

75 Referring to the drawings,—Figure 1 is a side elevation of a machine embodying my invention. Fig. 2 is a plan view thereof. Fig. 3 is a view of a portion of the machine giving an end elevation of the wrapping and collecting mechanism. Fig. 4 is a detailed view in section of the hopper and cigarette 80 delivery mechanism appurtenant thereto, and of the main conveyer mechanism. Fig. 85 5 is an enlarged detailed view of the strip feeding mechanism; Fig. 6 is a side elevation of the cigarette readjusting mechanism; and Fig. 7 is a modified form of vane wheel.

85 Like letters refer to like parts throughout the several views.

90 Inasmuch as my invention relates more particularly to improvements in the machine described in the Letters-Patent heretofore referred to, a detailed description of said machine and its mode of operation will not be entered into except in those respects wherein the improvement resides, reference 95 being had to said Letters-Patent to more fully explain the detailed construction and mode of operation of the remaining mechanisms shown.

95 In the accompanying drawings, I have 100 shown at A the cigarette hopper, at B the holder in which the cigarettes are held while having the ends thereof tipped, at C a pusher-rod and its actuating mechanism, at D the reel for the web, at E the shears and 105 their actuating mechanism, at F the actuating mechanism for the strip feeding mechanism, at G the paste feeding and spreading mechanism, and at H the oscillating wiper and its mechanism.

110 To simplify the description, the mechanisms will be considered with relation to the progress of the cigarettes through the machine; and will, therefore, be divided into the hopper mechanism adapted to receive 115 and store cigarettes and deliver to the next mechanism, which would be the conveying belt and holder mechanism. The next mechanism to be considered will be the transfer mechanism by means of which the cigarettes 120 are fed to the holder and adjusted relative thereto. The remaining mechanisms to be considered will be the strip feeding mechanism, which will include, generally, the shears or scissors for severing the portion 125 of the strip, and this mechanism will be described in conjunction with the wrapping mechanism, and finally the collecting mechanism.

130 The hopper A may be of any desired

depth, and is of a width substantially equaling the length of a cigarette. The bottom of this hopper is closed by an ordinary conveyer-belt 1, running around the pulleys 2-2, which conveyer is driven by the en- 5 chain gears 3. Mounted adjacent to the front end of the said hopper is an oscillating lifting-plate 4, extending to a point distant from the said conveyer-belt about 10 the width of a cigarette; and obstructing the passage from said hopper beyond said lifting-belt 4 is a wheel having a plurality of curved vanes 5, spaced away from the belt 1 sufficiently to allow an oval cigarette 15 to pass thereunder at its smallest dimension, and a delivery mechanism consisting of a cylinder 6 having a plurality of peripheral pockets adapted to receive a cigarette and a weighted flap 7, adapted to hold cigarettes 20 in said pockets until they are accurately positioned so as to be delivered from said pockets to the conveying-belt in the proper position. I provide a supplemental flap 8 to position the cigarettes properly in the 25 pockets of the cylinder 6. The function of the vanes 5 is to turn the cigarettes, in case they are delivered by the belt 1 in the wrong position. I provide this delivery mechanism in order that no cigarettes will 30 be broken or mutilated in passing from the hopper, and also to insure a regular, timely feeding of the cigarettes and their accurate positioning on the main conveyer-belt. The gear 9 actuating the cylinder 6 is driven 35 from the last of the enchain gears 3 by the gear 10, and, to synchronize the action of this delivery mechanism with that of the main conveyer-belt, I key the first gear of the enchain gears 3 on the shaft of one 40 of the pulleys of said main conveyer-belt. It will thus be observed that cigarettes will be delivered from the hopper A only when the main conveyer-belt is in operation and that the intervals of the delivery of said 45 cigarettes will be gaged with relation to the lineal travel of said belt and will be intermittent, in order to place the cigarettes upon said main belt at the proper time and in the proper position.

50 Arranged in a plane immediately below the hopper A are parallel rollers 10^a and 11, one of which, 10^a, is adjacent to said hopper and the other of which, 11, is adjacent to the holder B, so that a conveyer-belt 55 passing around said rollers will be alined with one side of said holder. Mounted upon said rollers is an endless conveyer-belt 12, the face of which is provided with a plurality of partition blocks 13, dividing 60 it into a plurality of similar equi-distant compartments adapted to receive cigarettes between them. The distance between these partition blocks 13 is substantially the width of the cigarettes to be tipped, only sufficient 65 clearance being allowed to compensate for the variance in the size of different cigarettes, due to the irregularities in the rope. The blocks 13 extend into close juxtaposition to the flap 7, so that in case a cigarette should be dropped thereon, it would be 70 pushed by said flap into the next compartment and rolled over flatwise. Adjacent to the roller 11 and spaced away therefrom a distance substantially equaling the height of the blocks 13 is a plate 14, the function 75 of which is to prevent the escape, or the rolling movement of the cigarettes in the compartments between the blocks 13, as said blocks are positioned to bring each compartment successively in alinement with the 80 holder B.

The detailed construction of the holder B is immaterial to this invention, that shown being the same as in my said patent wherein the jaws exert a spring controlled pressure 85 upon the cigarettes, and are opened and closed to permit the ejection of one cigarette through the incoming cigarette when it is fed to said holder.

The pusher-rod C is given a timely re- 90 ciprocation prior to the wrapping of the tip about the end of each cigarette in a manner described in my aforesaid patent.

The conveyer-belt leading from the hopper in my said patent was a perfectly flat 95 belt discharging into a chute alined with the holder B, and, as it was necessary, to secure the highest efficiency, to always have said hopper filled, carelessness on the part of the operator might result in a condition 100 where the chute would empty and cigarettes would be delivered thereto from the conveyer-belt after the pusher-rod had received its initial movement, thus causing the rod to mutilate the cigarettes. Inasmuch as the construction of the conveyer-belt 12, heretofore described, is designed, 105 primarily, to eliminate this chute and cause a timely, uniform feeding of the cigarettes relative to the operation of said pusher-rod, 110 it is necessary to feed this belt forward by an intermittent movement having an interval of rest during which the pusher-rod will be actuated and the cigarette ejected from the compartment between the blocks 13, and 115 delivered directly to the holder B. To accomplish this intermittent movement, I provide the shaft of the pulley 10^a with a ratchet-wheel 15, which wheel is adapted to be intermittently rotated by means of a 120 pawl 16, carried by a lever 17 having a forked end straddling the main shaft of the machine and carrying a roller 18 adapted to be engaged by a rise 19 on the cam B', the 125 location of said rise 19 on said cam being such that the feeding interval of the belt 12 will be at a time when said pusher-rod C is at rest. By this construction I provide a mechanism wherein a conveyer-belt having a plurality of compartments formed there- 130

on will be intermittently fed a distance equaling that between the centers of succeeding compartments, while the pusher-rod is held stationary and said belt will be brought to rest and said pusher-rod simultaneously actuated to eject a cigarette therefrom to the holder preparatory to the actuation of the wrapping mechanism.

In cigarette machines utilizing an endless 10 filler, there is always likelihood of a variance in the lengths of the different cigarettes, which is, for all practical purposes, immaterial, but which, when the tip is applied to the cigarette, may result in the 15 exposure of a narrow white strip between the mouthpiece and the end of the cigarette. This, in the finer class of work, would result in the formation of a second, as it is desirable to have the ends of the tipping material flush with that of the cigarette. 20 When the cigarette in the holder is ejected by the cigarette being fed thereto, the likelihood of the showing of so much white strip is increased, and, to adapt the machine to this condition of use, I provide an end 25 gage, which will not only act as a stop, as each cigarette is fed to the holder, but will readjust the cigarette by a slight return movement which will always bring the end 30 of the cigarette in the proper alinement with the strip being fed relative thereto to insure the front edge of said strip being brought exactly flush with the end of the cigarette. If desired, the pusher-rod may 35 be adjusted so as to insure a slight feeding movement of the cigarette to said holder in excess of that actually required to project the cigarette beyond said holder the width of the tip to be applied.

40 In order to allow the proper clearance for the ejection of cigarettes from the holder, it is necessary that the readjusting mechanism should normally be positioned out of alinement with the holder, and be brought 45 into the proper position by a movement timed relative to that of the pusher-rod so as to act both as an end-gage to check the forward movement of the cigarette, as it is fed to said holder, and to impart to it a return movement coincident with the withdrawal of the pusher-rod. With this end 50 in view, I mount in the end-gage 94, described in my said Letters-Patent, a headed stud 20, normally held flush with the inner face of said gage by means of the spring 21. Mounted on a stud 22 carried by the frame of the machine below said holder, is a lever 23 having a slot 24 therein engaging said stud 22, the upper end of which lever 55 is alined with the stud 20. Mounted on said machine is a bell crank lever 25, one arm of which is pivotally connected to said lever 23, and the other arm of which is provided with a roller 26 adapted to engage a face 60 cam 27 carried by the main shaft of the

machine above the shaft upon which the cam B' is mounted. It will thus be observed that with each oscillation of the bell crank lever 25, the lever 23 will receive a simultaneous upward and oscillatory movement, the bell crank lever 25 being so set that both arms are below the horizontal radius of the arc described thereby. By spacing the upward end of the lever 23 slightly away from the stud 20 the extent of readjustment 75 of the cigarette may be gaged. Inasmuch as the extent of movement of the upper end of the lever 23 will never exceed $\frac{3}{2}$ to $\frac{1}{16}$ of an inch, it will readily be seen that a short engagement of said lever with 80 said stud only is required. It will also be observed that the location of the cam 27 upon the same shaft as the cam B' insures a timely actuation of the lever 23 relative to that of the pusher-rod C and avoids any 85 variance through wear, lost motion or similar causes. Not only does the stud 20 accomplish the accurate positioning of the cigarette in the holder, but, when a rotary holder is employed, the withdrawal of said 90 stud after such readjustment leaves the end of the cigarette perfectly free and thus avoids the disturbance of the exposed tobacco which would result were the end-gage fixed and in constant engagement with the 95 cigarette. The cigarette having thus been accurately positioned, the next stage is the placing of the tip about the protruding end thereof. This mechanism is the same in most respects as that described in my afore- 100 said Letters-Patent, the wiper H having the same construction and mode of operation, and the vertically reciprocating carrier 91 having the same construction and mode of 105 operation except that the plate 99 thereof is provided with studs 199 arranged on opposite sides of the forward edge thereof relative to the strip feeding mechanism, between which the strip is fed, and which serves to guide it as the holder is rotated 110 after the section of strip has been severed from the continuous web. The shear mechanism E is the same as that described in my said Letters-Patent. The detailed construction of the reel D, paste-box G, and web 115 carrier plate 75, and its actuating mechanism is also the same as described in said Letters-Patent. A detailed description of these various mechanisms will not be entered into, in order to avoid prolixity. The 120 paste-pot mechanism, however, instead of being actuated by a chain drive, as in my aforesaid patent, is driven through a series of enchain'd gears 28, to avoid any lost motion through wear upon the chain or 125 sprockets.

Pivottally mounted on the frame of the machine above the carrier 75 is an oscillating lever one arm 29 of which is disposed above the slide 69, and adapted to be pro- 130

jected into the path of the carrier 75 so as to engage the handle 79, and release the fingers 78, and the other arm 30 of which projects downwardly into engagement with a series 5 of four tappets 31 on the shaft of the last gear 28. The forward end of the arm 29 is provided with a narrow plate 32 having a downwardly bent end adapted to engage the side of the projecting end of the cigarette 10 held in the holder B and at the same time bear upon the plate 99 when it is raised so as to lightly clamp the tipping material between the plate 32 and the plate 99. The last gear 28, being twice the diameter of the 15 first of the train, will reciprocate the lever and the arm 29 thereof twice to each wrapping operation, two such actuations being desirable, in order to afford a backing to the cigarette, and hold the tip against a possible 20 return movement with the carrier plate 75 when the forward end of the strip is applied to the cigarette and to afford such a backing to the cigarette when the wiper H forms the lap joint of the tipping material, 25 thus not only insuring the severance of a piece of tipping material of equal length with each reciprocation of the carrier 75, but preventing the wiper H from bending or breaking the protruding end of the cigarette, in case an extra large cigarette should 30 be in the holder. It will be observed that by this construction I provide an intermittently operated backing plate adapted to engage the cigarette on the side thereof opposite to 35 that operated upon by the wiper H, the means operating said backing plate being so synchronized with the other mechanisms of the machine as to leave clearance for the insertion and ejection of the cigarettes from 40 the holder. It will also be observed that the arm 29 of the backing lever, when the wiper first applies the end of the strip to the cigarette, is in engagement with the handle 79 so that the fingers 78 will be raised at this 45 time and held uplifted until the portion of the end of the cigarette for the tip has been severed from the strip and the arm 29 raised out of engagement therewith. The remaining 50 operations of the machine necessary to the application of the tip to the cigarette end are the same as described in my aforesaid Letters-Patent, (no claim thereto being made in this application) and such will not be entered into. After the application of 55 the tip to the cigarette, the completed tipped cigarette is ejected from the holder B by the next cigarette fed to said holder, the wiper H, as described in my aforesaid patent, being raised into engagement with the 60 cigarette being discharged, so as to minimize the momentum which would otherwise be imparted to the cigarette through the speed of operation of the machine. The manner of ejection is such as to make it difficult 65 to collect the cigarettes in the ordinary

box used on the ordinary cigarette making machine, and, to avoid handling and re-packing, I provide a special collecting mechanism, the essential features of which are a receiving box, means whereby the cigarettes 70 are distributed within said box, and a pair of oppositely disposed converging pivoted plates, so balanced as to be opened by the weight of a cigarette at the adjacent ends thereof, so that each cigarette discharged 75 into the hopper formed by said plates will be delivered in exactly the same position as every other cigarette.

Mounted on suitable brackets extending from the frame of the machine forwardly of 80 the holder B is a box frame 33, open at the top and having the bottom thereof closed by one long conveyer-belt 34, and two short conveyer-belts 35 and 36, which belts extend in parallel lines and run at equal speed. 85 These belts, at one end thereof, run about the same or concentric pulleys of the same diameter. These pulleys will be at the end of the box adjacent to the holder B. The belt 34 will, therefore, project into the other 90 end of the box with a space between each side thereof and the sides of the box frame 33. This arrangement of belts is designed to impart an equal feeding movement to the cigarette throughout its entire length, and 95 thus prevent any skewing of the cigarette through frictional engagement with a fixed surface, or the clogging of the conveying mechanism by having cigarettes piled at one side of the belt. The belt 34 is extended beyond the others, in order that it may extend 100 into an opening in the bottom of the collecting box 37 and deposit the cigarettes well within said box.

In conjunction with the frame 33, I employ a detachable collecting box 37 having a bottom slotted throughout a portion of its length corresponding to the extent of projection of the belt 34 beyond the belts 35, 36. This box is provided with side hooks 105 38^a adapted to pass over and engage the top of the box-frame 33. It will be seen by reference to the drawings that the portions of the bottom of the box 37 on each side of the belt 34 are, therefore, alined with the belts 110 35, 36, respectively, so that the three belts 34, 35 and 36 will deliver the cigarettes to the box 37, and the middle belt 34 will pack or stack them in said box.

Mounted in the frame 33 adjacent to the 115 holder B are the two plates 38, 39, which are pivoted in said frame by means of the pivots or trunnions 40 and 41, respectively. The top of each said plate is curved outwardly slightly and extended laterally to form contact shoulders 42 and 43, respectively, and the bulk of metal in the enlarged head is such as to slightly overbalance each plate so as to cause the lower ends thereof to automatically and normally come into such close 120

125 130

6

juxtaposition as not to permit a cigarette to pass therebetween. Leading from a point adjacent to the holder B is a closed chute 44 having a direction which will project cigarettes ejected from said holder upon one of the plates, as 39. The bulk of metal at the top of the plates, 38, 39, must be sufficiently great to sustain the weight of a cigarette upon either plate below the pivotal point, except at substantially the bottom thereof, whereby the descent of the cigarettes in the hopper formed by said plates will be so retarded as to true up each cigarette so that when it approaches the bottom of the plates, it will oscillate the plates and be dropped thereby upon the belts 34, 35 and 36, whence it will be conveyed to the box 37.

The operation of the herein described machine is substantially as follows: Cigarettes are placed in the hopper A in a position paralleling the holder B and the machine set in operation in the usual manner. The belt 1 is then rotated toward the holder B by the enchain gears 3, and the cylinder 6 is also rotated through said gear system, the vanes 5 being rotated in the same direction as the cylinder 6 by the belt and pulley shown in the drawings. At the same time, the plate 4 is oscillated through said pulley to constantly lift the cigarettes in the hopper and prevent a clogging of the outlet through the jamming of said cigarettes. The lifting plate 4, being spaced away from the belt 1, permits the cigarettes to pass thereunder, the vanes 5 serving not only to true up cigarettes, but to permit only one at a time to pass from the belt 1 to the cylinder 6, and only in the position in which they are adapted to enter the pockets in said cylinder. Each cigarette, as it enters the pocket in said cylinder, is carried over toward the main conveyer belt 12, the flap 8 serving to limit the cigarettes carried over to one in each pocket, and the flap 7 serving to hold the cigarette in said pocket and permit it to drop therefrom only when the compartment formed by any two adjoining blocks 13 is directly beneath the discharge point of said cylinder 6. It will be observed that the operation of the mechanism feeding cigarettes to the belt 12 is synchronized with that of said belt, being geared to one of the pulleys thereof so that said feeding mechanism is operative only while said belt is in motion, the intermittent feeding movement of said belt 12 making such a construction essential. Cigarettes having been fed from the hopper to the belt 12, in the manner described, said belt will be advanced by means of the ratchet 15, pawl 16, lever 17 and cam 19, the result of the actuation of this mechanism being the intermittent advancement of the belt 12 and the cigarettes contained thereon to an extent equaling the dis-

tance between the centers of the compartments formed by the blocks 13 thereon. As the conveyer-belt 12 passes around the pulley 11, the compartments between succeeding blocks 13 are brought successively into alignment with the holder B. When a compartment is so located, the pawl and ratchet mechanism becomes inoperative and the belt 12, the feeding mechanism and the hopper A are brought to rest while the cigarette contained in said compartment is delivered to the holder B by means of the pusher-rod C and said pusher-rod is withdrawn preparatory to the delivery of the next cigarette from the belt 12 to the said holder. As the cigarette is being fed to the holder B, the carrier 92 is raised to position the end 94 and the stud 20, carried thereby, before said holder, in a manner to act as a positive stop to limit the extent of projection of said cigarette from the holder. This operation is simultaneous with the raising of the wiper H which acts as a retard by engaging the side of the cigarette. Substantially simultaneous with the reversal of the direction of movement of the pusher-rod C, the bell-crank lever 25 is oscillated by the cam 27 to raise the lever 23 upwardly and oscillate it toward the stud 20 in a manner to advance said stud toward the cigarette and cause said cigarette to follow the pusher-rod by a slow movement until the cigarette is readjusted to the holder with the end projecting only to the desired limited extent, which extent will be uniform in all cigarettes, irrespective of the interval of engagement of the said stud 20 with the end of the cigarette. Instantly with the accomplishment of this readjustment, the lever 23 is restored to normal and the spring 21 allowed to restore the stud 20 to its former position. The carrier 92 is then lowered to allow a clear field for the positioning of the strip and preparatory to the wrapping operations. As the cigarette is being adjusted to the holder, the carrier 75 is being slowly advanced toward said holder, drawing the continuous web from the reel D with it through the engagement of the fingers 78 with said strip, the strip being fed pasted side upward with one end thereof projecting forwardly of the said carrier 75. The strip end is fed between the shears E and positioned directly above the plate 99, with the projecting end of the strip projecting into the path of the wiper H, so that with the upward oscillation of said wiper, the forward end of the strip will be folded about and applied to one side of the cigarette and held by the wiper against the cigarette while the plate 75 is withdrawn preparatory to the severing of the strip end by the shears E, the measuring of the next tipping section of the strip being accom-

plished by the movement of the carrier 75 independently of and relatively to the strip which is held stationary at this interval.

In the machine described in my aforesaid patent, I have found that in loosely packed or small cigarettes, the protruding end of the cigarette does not offer sufficient resistance to the wiper 104 of the mechanism H to secure a sufficient adhesion of the strip end there-
 10 to to overcome the slight drag of the fingers 78 on said strip, thus resulting in an occasional "second" through the failure of the wrapping mechanism to apply a tip to the cigarette end, or a slight slippage of the end
 15 of the strip, resulting in the absence of the lap to the strip portion applied thereto. In my present machine, as the carrier 75 approaches the end of its feeding movement, the arm 29 will be raised against the tension
 20 of the spring 45 by one tappet 31 engaging the arm 30, thus elevating the downwardly turned plate 32 above the plane of the holder B. As the said carrier 75 reaches the limit of its direct feeding movement, the
 25 tappet 31 passes from its engagement with the arm 30 and permits the spring 45 to lower the arm 29 so that the end plate 32 will descend to a position where the forward face of said plate will engage the cigarette
 30 and the bottom edge thereof will press upon the strip, lightly clamping it upon the plate 99. The descent of the arm 29 will, by engagement with the operating handles 79 of the fingers 78, raise said fingers out of engagement with the strip and hold them in the raised position. As the plate 32 is thus positioned, the wiper 104 of the mechanism H is raised and applies the end of the strip of tipping material to the side of the cigarette, the plate 32 not only preventing any slippage of the strip, but acting as a platen or backing to the cigarette to prevent the wiper bending or breaking same. At this interval and preparatory to the rotation of the holder B the carrier 75 recedes, upon its return movement, the arm 29, holding the fingers raised so as to preclude any possibility of the fingers 78 imparting any backward movement to the strip. While the fine points of these fingers would ordinarily preclude any such tendency, I have found that, after a long run, the tips of the fingers are apt to accumulate paste or glue to an extent to cause them to have greater adherence than the mere finger ends themselves would have, thus preventing the automatic disengagement of the fingers with the strip and causing the plate 75 to occasionally pull the strip back, as heretofore stated.
 50 The raising of the fingers obviates this difficulty, however, and as they are raised when the carrier 75 and the fingers 78 are close to the platen 99, this disengagement will not only be accomplished without disturbing the strip or throwing it out of aline-
 55 ment, but the location of the arm 29 will be such as to permit the fingers to automatically reengage the tip when the carriage 75 has reached the limit of its return movement, irrespective of the position of said arm. As in the machine described in my aforesaid patent, with the completion of the return movement of the carrier 75, the shears E are actuated to sever the strip end while the strip is tensioned more or less so as to secure a straight edge, the point of the plate 32 serving to hold the strip, thus compensating for the absence of the tensioning effect due to the return movement of the plate 75 and the engagement of the fingers 78 with the strip. The end of the strip is severed substantially simultaneously with the engagement of the succeeding tappet 31 with the arm 30, which engagement raises the end 32 out of engagement with the cigarette and the plate 99, leaving a clear field for the rotation of the cigarette with the holder B and the application of the severed end to the protruding end of the cigarette in the manner described in my aforesaid patent prior to the final lowering of the wiper 104 of the mechanism H, the oppositely disposed studs 199 guiding the severed end of the strip to cause it to be wound in perfect alinement upon the cigarette end.
 60 As described in my aforesaid Letters-Patent, the holder B at the end of one complete rotation comes to complete rest preparatory to the sealing of the lap of the tip by the wiper 104 of the mechanism H, and, slightly in advance of the final descent of said wiper, the arm 30 will escape from the tappet 31 engaging same, and permit the plate 32 to be again brought into engagement with the side of the cigarette to afford a backing thereto during the final wiping, or the sealing of the tip to form said lap. The various other mechanisms, with the completion of these wrapping operations, are restored to normal and the cigarette then in the holder is ejected by the next cigarette being fed to said holder. The tipped cigarette, as it leaves the holder B, is delivered to the chute 44 and delivered thereby to one of the plates 38, 39, within the collecting box 33.
 65 As it drops upon said plate, its weight will be insufficient to overcome the counterweights at the top thereof until it approaches the bottom of the adjoining plate, at which point the leverage will be sufficiently great to oscillate one or both of said plates and drop the cigarette therefrom in a line parallel with the holder upon the collecting belts 34, 35 and 36, whereby it will be conveyed to the removable box 37 and deposited at the extreme end thereof not occupied by the belt 34. The pawl and ratchet mechanism actuating the main belt 12 will become operative immediately upon the withdrawal of the pusher-rod C to feed said 120
 70 125
 75 130

belt forward the distance between the centers of the compartments formed by the blocks 13 and simultaneously deliver a cigarette to the next succeeding compartment 5 adjacent to the hopper A, by the delivering mechanism of said hopper, as heretofore described.

The foregoing operations are repeated with great rapidity and the box 37 will be 10 gradually filled with cigarettes. When so filled, it is removed and another substituted in its stead, the cigarettes in the box 37 being in a position where they can be either conveniently handled for packing direct 15 from the box or deposited in another box provided for the purpose without handling the individual cigarettes.

By the improvements herein described, I aim merely to overcome those limitations 20 placed upon the machine in my aforesaid patent by the conditions due to extended runs and unskilled labor, the actual operations by which the tip is applied to the cigarette being substantially the same as in 25 my said patent, and the efficiency of the machine in this respect not being enhanced by the improvement. I have found that in my said machine, the percentage of "seconds" in a day's run will vary from perfect 30 work to from three to five per cent., and that most of said "seconds" are due to the improper feeding of the cigarettes to the holder and the imperfections in the cigarettes themselves, the machine having been 35 incapable of automatically adjusting itself to such variances. By my said improvements, I not only materially reduce the number of seconds, but provide a machine requiring less attention from the operator, 40 such attention being limited to the necessity for turning the cigarettes to position the monograms or the seams uniformly on the belt 12 so as to cause the overlap or lap to be uniform on all cigarettes tipped. 45 It is not my intention to limit the invention to the precise details of construction of the improvements shown in the accompanying drawings, such being capable of variation without departing from the spirit or 50 scope of the invention.

Having described the invention, what I claim as new and desire to have protected by Letters-Patent is:

1. In a cigarette machine, the combination 55 with a feeding mechanism for the tipping material, means whereby said material is made adhesive, and means applying a portion of adhesive strip to the end of a cigarette, including therein a holder, of a 60 hopper adapted to store cigarettes to be tipped, a conveying belt having a plurality of compartments formed thereon, adapted to be successively alined with said holder, said belt extending from said hopper to said 65 holder, means whereby the cigarettes are de-

livered one at a time from said hopper to said compartments successively, a delivery mechanism whereby cigarettes are transferred from the compartments of said belt to said holder successively, and means intermittently actuating said conveyer-belt whereby said belt is held stationary during the transfer of the cigarettes therefrom to said holder. 70

2. In a cigarette machine, the combination 75 with a feeding mechanism for the tipping material, means whereby said material is made adhesive, and means applying a portion of adhesive strip to the end of a cigarette, including therein a holder, of an open bottom hopper adapted to store the cigarettes to be tipped, a conveying belt having a plurality of compartments formed thereon adapted to be successively alined with said holder, said belt extending from below said hopper to said holder, a conveyer belt closing a portion of the bottom of said hopper and leaving an outlet therefrom, a delivery mechanism arranged in said outlet whereby cigarettes will be properly positioned, and delivered one at a time to the compartments of said first mentioned belt, means intermittently and simultaneously actuating said conveyer belts, respectively, and said delivery mechanism whereby said first mentioned belt will be held stationary while cigarettes are being transferred therefrom to said holder, and said last mentioned belt and said delivery mechanism will deliver said cigarettes to said 100 compartments one at a time, and a delivery mechanism for transferring cigarettes from the compartments of said belt to said holder while said first mentioned belt is held stationary. 105

3. In a cigarette machine, the combination 110 with a feeding mechanism for the tipping material, means whereby said material is made adhesive, and means applying a portion of adhesive strip to the end of a cigarette, including therein a holder, of an open bottom hopper adapted to store the cigarettes to be tipped, a conveying belt having a plurality of compartments formed thereon adapted to be successively alined with said holder, said belt extending from below said hopper to said holder, a conveyer belt closing a portion of the bottom of said hopper and leaving an outlet therefrom, an oscillating plate extending to a point adjacent to said belt within said hopper whereby the piling of cigarettes adjacent to said outlet is prevented, and a delivery mechanism adapted to receive cigarettes as they pass said plate, true them up, and drop 120 them successively into said compartments of said first mentioned belt, means intermittently and simultaneously actuating said conveyer belts, respectively, and said delivery mechanism whereby said first men- 125

130

- tioned belt will be held stationary while cigarettes are being transferred therefrom to said holder, and said last mentioned belt and said delivery mechanism will deliver 5 said cigarettes to said compartments one at a time, and a delivery mechanism for transferring cigarettes from the compartments of said belt to said holder while said first mentioned belt is held stationary.
- 10 4. In a cigarette machine, the combination with a feeding mechanism for the tipping material, means whereby said material is made adhesive, and means applying a portion of adhesive strip to the end of a cigarette, including therein a holder, of an open bottom hopper adapted to store the cigarettes to be tipped, a conveying belt having a plurality of compartments formed thereon adapted to be successively alined with said 15 holder, said belt extending from below said hopper to said holder, a conveyer belt closing a portion of the bottom of said hopper and leaving an outlet therefrom, an oscillating plate extending to a point adjacent to said 20 belt within said hopper whereby the piling of cigarettes adjacent to said outlet is prevented, and a delivery mechanism comprising a cylinder having pockets therein adapted to receive cigarettes from the hopper belt, and deposit them in the compartments of 25 said first mentioned conveyer belt, and means positioning and retaining the cigarettes in said pockets preparatory to their discharge therefrom, means intermittently 30 and simultaneously actuating said conveyer belts, respectively, and said delivery mechanism whereby said first mentioned belt will be held stationary while cigarettes are being transferred therefrom to said holder, and said last mentioned belt and said delivery 35 mechanism will deliver said cigarettes to said compartments one at a time, and a delivery mechanism for transferring cigarettes from the compartments of said belt to said holder while said first mentioned belt is held 40 stationary.
- 45 5. In a cigarette machine, the combination with a feeding mechanism for the tipping material, means whereby said material is made adhesive, and means applying a portion of adhesive strip to the end of a cigarette, including therein a holder, of an open bottom hopper adapted to store the cigarettes to be tipped, a conveying belt having a plurality of compartments formed thereon adapted to be successively alined with said holder, said belt extending from below said hopper to said holder, a conveyer belt closing a portion of the bottom of said hopper 50 and leaving an outlet therefrom, an oscillating plate extending to a point adjacent to said belt within said hopper whereby the piling of cigarettes adjacent to said outlet is prevented, and a delivery mechanism comprising a cylinder having pockets therein 55 adapted to receive cigarettes from the hopper belt, and deposit them in the compartments of said first mentioned conveyer belt, a wheel having a plurality of curved vanes spaced above said hopper conveyer forwardly of said cylinder whereby more than one cigarette at a time is prevented from entering the pockets in said cylinder, and a plurality of weighted flaps disposed about the periphery of said cylinder whereby the cigarettes are accurately positioned in said pockets and retained therein to a point adjacent to the point of discharge of the cigarette from said pockets, means intermittently and simultaneously actuating said conveyer belts, respectively, and said delivery mechanism whereby said first mentioned belt will be held stationary while cigarettes are being transferred therefrom to said holder, and said last mentioned belt and said delivery 60 mechanism will deliver said cigarettes to said compartments one at a time, and a delivery mechanism for transferring cigarettes from the compartments of said belt to said holder while said first mentioned belt is held stationary.
- 65 6. In a cigarette machine, the combination with a feeding mechanism for the tipping material, means whereby said material is made adhesive, and means applying a portion of adhesive strip to the end of a cigarette, including therein a holder, of a conveyer belt having a plurality of compartments formed thereon adapted to be successively alined with said holder, a plate adjacent to said holder extending parallel to said conveyer belt whereby cigarettes are retained therein when approaching said holder and when alined therewith, a delivery mechanism whereby cigarettes are transferred 70 from the compartments of said belt to said holder successively, and means intermittently actuating said conveyer-belt whereby said belt is held stationary during the transfer of the cigarettes therefrom to said holder.
- 75 7. In a cigarette machine, the combination with a feeding mechanism for the tipping material, means whereby said material is made adhesive, and means applying a portion of adhesive strip to the end of a cigarette, including therein a holder, of a conveying belt having a plurality of compartments formed thereon adapted to be successively alined with said holder, a hopper adapted to store cigarettes to be tipped, said belt extending from said hopper to said holder, means whereby the cigarettes are delivered one at a time from said hopper to said compartments successively, a delivery mechanism whereby cigarettes are transferred from the compartments of said belt to said holder successively, means intermittently actuating said conveyer belt whereby said belt is held stationary during the transfer of the cigarettes therefrom to said holder,
- 80 85 90 95 100 105 110 115 120 125 130

means intermittently rotating said holder, and means actuating said wrapping mechanism simultaneously with the actuation of said conveyer belt whereby cigarettes will be delivered to said belt and the succeeding compartment of said belt will be alined with said holder while said wrapping mechanism is tipping the cigarette delivered from the preceding compartment.

10 8. In a cigarette machine, the combination with a holder, means whereby cigarettes are alined with said holder, a pusher rod adapted to transfer cigarettes from said means to said holder, a feeding mechanism for the tipping material, means whereby said material is made adhesive, and means in conjunction with said holder whereby a portion of strip is wrapped about the end of a cigarette, including therein a vertically reciprocated plate having an end gage, a reciprocating stud mounted in said gage and a spring normally forcing said stud away from said holder, of a lever having a vertical and an oscillatory movement adapted to be alined 25 with said stud, and means actuating said lever whereby said lever will be below said holder as the cigarettes are ejected therefrom and each cigarette, as said plunger recedes, will be caused to follow said plunger 30 to a limited extent to true up the cigarettes in said holder prior to the actuation of said wrapping mechanism.

9. In a cigarette machine, the combination with a holder and means whereby cigarettes are successively delivered thereto and ejected therefrom, of means whereby a strip of tipping material is fed relative to the forward end of said holder including therein a reciprocating plate and a clutch thereon 40 adapted to engage the strip, means making said strip adhesive, a wiper adapted to apply the ends of said strip to a cigarette, means adapted to release said clutch whereby said strip is relieved from strains during the 45 turn movement of said plate, means adapted to sever a portion of the end of said strip, and means adapted to apply said severed portion to the cigarette.

10. In a cigarette machine, a wrapping mechanism including therein an oscillating wiper adapted to apply one end of the tipping material to the cigarette, and a plate adapted to engage and form a backing for the cigarette opposite said wiper.

55 11. In a cigarette machine, a wrapping mechanism including therein an oscillating wiper adapted to apply one end of a strip of tipping material to the cigarette, and a vertically reciprocating plate adapted to bring the strip close to the cigarette, a strip feeding mechanism including therein a reciprocating plate having a clutch thereon adapted to engage the strip, means adapted to simultaneously clamp the strip upon said 65 vertically reciprocating plate, release said

clutch, and engage and form a backing for the cigarette whereby said feeding plate may be withdrawn without placing strains upon the tip, and said strip end may be applied to the cigarette without mutilating it, means 70 making the strip adhesive, and means whereby a portion of the end of the strip is severed.

12. In a cigarette machine, a wrapping mechanism including therein an oscillating 75 wiper adapted to apply one end of a strip of tipping material to the cigarette, and a plate positioned below the cigarette end, a strip feeding mechanism including therein a reciprocating plate having a clutch thereon 80 adapted to engage the strip, the upper jaw of said clutch having an upwardly extended tongue whereby it may be raised, an oscillatory arm above said plate adapted to engage said tongue, said arm carrying a plate 85 adapted to be brought into engagement with the cigarette, and with the strip on said first mentioned plate, and means whereby said arm will be reciprocated twice during each wrapping operation to release said clutch, 90 and engage and form a backing for the cigarette each time said wiper applies an end of the tipping material thereto.

13. In a cigarette machine, the combination with means whereby a tip is placed 95 upon the end of a cigarette, of a collecting mechanism comprising a frame, a plurality of parallel conveyer belts mounted therein, means driving said belts at uniform speed, a box mounted on said frame with its bottom in substantial alinement with said belts, 100 said box being open at the end adjacent to said belts, and a hopper adapted to receive finished cigarettes, true them up and automatically open and deposit them upon said 105 belts.

14. In a cigarette machine, the combination with means whereby a tip is placed upon the end of a cigarette, of a collecting mechanism comprising a frame, a plurality of parallel conveyer belts mounted therein, one of said belts being longer than the others, means driving said belts at uniform speed, a box mounted on said frame with its bottom in substantial alinement with said 110 belts, said box being open at the end adjacent to the short belts and having a slotted bottom adapted to pass over the longer belt, and a hopper adapted to receive finished cigarettes, true them up, and automatically 115 open and deposit them upon said belts.

15. In a cigarette machine, the combination with means whereby a tip is placed upon the end of a cigarette, of a collecting mechanism comprising a frame, a collecting belt and a collecting box into which said belt discharges carried thereby, and a hopper discharging upon said belt comprising a plurality of oppositely disposed conveying pivotal plates so balanced as to be opened 125 130

by the weight of a cigarette on the adjacent ends thereof, whereby said hopper will be automatically opened by the weight of the cigarette to deposit each cigarette upon said belt and closed.

16. In a cigarette machine, the combination with means whereby a tip is placed upon the end of a cigarette, of a collecting mechanism comprising a frame, collecting 10 belts and a collecting box into which said belts discharge carried thereby, and a hopper discharging upon said belts comprising a plurality of converging pivotal plates, having an excess of weight and a stop shoulder above the pivot, whereby said hopper will automatically close, and be automatically opened by the weight of the cigarette to deposit each cigarette upon said belt.

17. In a cigarette machine, the combination with a feeding mechanism for the tipping material, means whereby said material is made adhesive, and a wrapping mechanism, of a holder, an open bottom hopper adapted to store the cigarettes to be tipped, 20 a conveying belt having a plurality of compartments formed thereon adapted to be successively alined with said holder, said belt extending from below said hopper to said holder, a conveyer belt closing a portion of 25 the bottom of said hopper and leaving an outlet therefrom, and a delivery mechanism comprising a cylinder having pockets therein adapted to receive cigarettes from the hopper belt, and deposit them in the compartments of said first mentioned conveyer 30 belt, rotary means spaced above said hopper conveyer belt forwardly of said cylinder whereby more than one cigarette at a time is prevented from entering the pockets in 35 said cylinder, and a plurality of yielding obstructions disposed about the periphery of said cylinder whereby the cigarettes are 40

accurately positioned in said pockets and retained therein to a point adjacent to the point of discharge of the cigarette from said 45 pockets, means intermittently and simultaneously actuating said conveyer belts, respectively, and delivery mechanism whereby said first mentioned belt will be held stationary while cigarettes are being transferred therefrom to said holder, and said last mentioned belt and said delivery mechanism will deliver said cigarettes to said compartments one at a time, and a delivery mechanism for transferring cigarettes from the 50 compartments of said belt to said holder while said first mentioned belt is held stationary.

18. In a cigarette machine, the combination with a holder, means whereby cigarettes 60 are alined one at a time with said holder, a transfer mechanism whereby cigarettes are transferred from said means to said holder, and means whereby a tip is placed upon the end of a cigarette, of a chute alined with 65 the forward end of said holder, and a collecting mechanism comprising a frame, collecting belts and a collecting box into which said belts discharge carried thereby, and a hopper discharging upon said belts comprising a plurality of oppositely disposed 70 conveying pivotal plates so balanced as to be opened by the weight of a cigarette on the adjacent ends thereof, whereby said hopper will be automatically opened by the 75 weight of the cigarette to deposit each cigarette upon said belt and closed.

In witness whereof, I have hereunto affixed my signature this 6th day of October, 1908, in the presence of two witnesses.

SALVADOR RAGONA.
